UNITED STATES PATENT OFFICE.

ALFRED HAMMERSTEIN, OF NEW YORK, N. Y., ASSIGNOR OF ONE-HALF TO
EMANUEL IKELHEIMER, OF SAME PLACE.

DESIGN FOR A LAMP-SCREEN.

SPECIFICATION forming part of Design No. 19,996, dated July 1, 1890.

Application filed May 31, 1890. Serial No. 353,860. Term of patent 3½ years.

To all whom it may concern:

Be it known that I, ALFRED HAMMERSTEIN, a subject of the German Emperor, residing at the city of New York, in the county and State 5 of New York, have invented and produced a new and original Design for Lamp-Screens, of which the following is a specification, reference being had to the accompanying drawing, forming part of the same.

10 The drawing fully represents my design in face view.

The main feature of my design consists in the representation of a bust, waist, and head

A of a female figure within a circle of scalloped disks B, representing skirts, the one 15 superposed upon the other, as shown. The female figure holds a bouquet D over her head; therefore,

Having fully described and explained my design, what I claim is—

20 The design for a lamp-screen, substantially as shown.

ALFRED HAMMERSTEIN.
